CLOSURE

Charles S. Loudenslager, Sr., and Charles S.
Loudenslager, Jr., Columbus, Ohio

Application March 17, 1934, Serial No. 716,180

12 Claims. (Cl. 231—60)

This invention relates to closures. It applies especially to containers of the collapsible type wherein a squeezing process is resorted to in order to discharge the contents. At this time 5 various types of such containers are extensively used in the vending of tooth paste, shaving creams, lotions, etc.

Today these containers are usually closed with what is known as a "screw cap". In order to 10 remove the cap it must be unscrewed. To close the container it must be screwed back on. Trouble, inconvenience and annoyance result when it is misplaced.

Many types of closing devices have been made 15 with the thought of automatically opening and closing the discharging end of the container. A survey of the closure field reveals the fact, however, that today none are being used to any extent. Apparently these devices are either impractical or else their construction does not permit economical manufacture.

This invention is designed to eliminate the disadvantages experienced with devices heretofore produced and bring the art to a higher state 25 of perfection. It has been conceived with the desire to provide an automatic closing device that is simple in design, strong in construction, positive in action and cheap in manufacture.

It is also intended to provide an automatic 30 closing device that can be readily used as an integral part of the container or as a separate unit without departing from the design or construction.

The invention comprehends such construction 35 that the finished product reveals but few simple parts that can be readily made and assembled by machinery now in use.

The concept of the invention provides for an 40 automatically operative closing device having the outward appearance of a paraboloid.

The concept embodied in this invention is illustrated in the accompanying drawing which 45 forms a part of this application.

Figure 1: This is a sectional elevation showing 50 the neck constructed as a separate unit from the container.

Figure 2: This is a sectional elevation illustrating the movable sleeve or core with the conoid top, the upper, protruding sealing lip at the rim 55 of the conoid and the lower spring support flange.

Figure 3: This is a plan view of an alternate flange construction of the lower spring support at the base of the movable sleeve or core.

Figure 4: This is a sectional elevation illustrating the truncated housing and sealing mem-

ber, including the upper spring-retaining shoulder, the aperture sealing mass and the sealing lip at the upper extremity of the member.

Figure 5: This is a side elevation, partly in section, revealing the device assembled in its normal 5 closed position.

Figure 6: This is a fragmentary sectional view illustrating the cooperative action of the outer sealing function.

Figure 7: This is a sectional elevation showing 10 the neck constructed as an integral part of the container.

Referring to the numerals on the accompanying drawing, number 3 denotes the neck which has a shoulder 2 designed at its base, the same 15 being designed to be a separable part of the container 1.

Number 4 indicates a sliding sleeve, open at the bottom end and mounted around the neck 3, above the shoulder 2. Features embodied in 20 the sliding sleeve 4 comprise a conoid top 13 with its bottom edge being a sealing lip 5, a flange 6, located at its bottom end and a discharge orifice 7 located in the side wall beneath the sealing lip 5.

Number 12 denotes a truncated paraboloid 25 which features an internal shoulder 10, an orifice sealing mass 9 and a sealing rim 8, the whole comprising the upper portion thereof. By structural design the entire lower portion becomes the 30 spring housing compartment 15. By means of threads or annular grooves it is attached at its bottom end to the shoulder 2 located at the base of the neck 3.

Number 14 denotes a coil spring which is 35 mounted around the sliding sleeve 4 and is retained in position by having its lower end resting upon the flange 6 and its upper end engaging the internal shoulder 10.

In dispensing, pressure is applied to the container 1, forcing the contents upward through the neck 3. When the pressure has increased sufficiently to overcome the expansive force of the spring 14, the sliding sleeve 4 is forced upward, breaking the outer seal by separating the 45 sealing lip 5 from the sealing rim 8. As the upward movement continues, the discharge orifice 7 is exposed to view after having passed the orifice sealing mass 9, thus permitting the contents to be expelled. Immediately upon the cessation of pressure upon the container 1, the spring 14, which by the operation has been compressed between the internal shoulder 10 of the housing and sealing unit 12 and the flange 6 at the base of the sliding sleeve 4, exerts its ex- 50 55

pansive energy and completely reverses the discharging operation by forcing the sliding sleeve 4 to its lowermost position and by so doing automatically closes the device.

5 We claim:

1. An automatic closing device for collapsible containers and the like, comprising in combination a cylindrical neck having a shoulder at its base, a cylindrical, sliding sleeve suspended 10 around said neck, above said shoulder, in such a manner that it may reciprocate thereon, and having an open lower end and a closed upper end, an orifice in the side wall, adjacent the upper end, said orifice being closed by a member 15 forming a part of said closing device when the said sliding sleeve is in its lowermost position and open when it is in its uppermost position, means for limiting the lowermost position of said sliding sleeve, a coil compression spring 20 mounted in surrounding relation to said sleeve and having its lower end abutting a flange extending outwardly on the lower end of said sliding sleeve, a cylindrical housing member mounted on said shoulder of said neck in spaced relation to the outer periphery of said compression spring, and having an internal flange at its upper end contacting and retaining the upper end 25 of said compression spring, said compression spring thus restricted being adapted to normally maintain said sliding sleeve in its lowermost position, all the parts of said closing device being combined as a separate unit which is attached to the neck of said container.

2. An automatic closing device for collapsible containers and the like, comprising in combination a neck with an inlet and an outlet, a shoulder forming its base, a sliding sleeve suspended around said neck above said shoulder, said sleeve having an open lower end and an upper end 35 closed by a bullet like top, the lower edge of said top having a lip extending outward beyond the side wall providing the means of suspending said sleeve at its lowermost position, an orifice in the side wall adjacent the top of said sleeve, a coil 40 spring mounted around said sleeve, its lower end abutting a flange extending outwardly on the lower end of said sleeve, a housing unit mounted on said shoulder at the bottom of said neck in spaced relation to the outer periphery of said 45 spring, having an internal shoulder at its upper end engaging the upper end of said spring, said spring being thus adapted to normally maintain said orifice in said sleeve in its normal closed position by maintaining said sleeve in its lowermost position, all the parts of said closing device 50 being combined as a separate unit, attachable to the neck of said container.

3. An automatic closing device for collapsible containers and the like, comprising in combination a cylindrical member having an external, right angled shoulder at its base, an outlet neck extending upward, beyond said shoulder, a tubular member having an open lower end, an orifice in the side wall at the top, its upper end being 60 closed by a bullet shaped cap, the lower edge of said cap projecting outward beyond the side wall providing limiting means for slidably suspending said member at its lowermost position around said outlet neck on said cylindrical member, a coil spring mounted in surrounding relation to 65 said tubular member, its lower end positioned on a flange extending outward on the lower end of said tubular member, a sealing member mounted on said shoulder at the base of said cylindrical member in spaced relation to the outer per-

iphery of said coil spring, said sealing member having an internal shoulder at its upper end which engages the upper end of said coil spring and adapting it to maintain said tubular member in its normally closed position, which places said orifice beneath the rim of and within the confines of the wall of said internal shoulder of said sealing member, all the parts of said closing device being combined as a separate unit which is attached to the neck of said container.

4. An automatic closing device for collapsible containers and the like, comprising in combination a tubular neck with a shoulder extending outward at right angles in a circular manner forming its base, and being channeled square in 15 section, in a circular manner on its under side, an outlet neck extending upward beyond said shoulder, a tubular sleeve open at the bottom, an aperture in the side wall at the top, its upper end closed by a conical formation, the lower 20 rim of which protrudes laterally beyond the side wall providing means of suspending said sleeve at its lowermost position around said neck, a coil spring mounted in surrounding relation to said sleeve, the lower end being supported by an 25 external flange at the bottom of said sleeve, a housing and sealing element mounted on said shoulder forming the base of said neck, in spaced relation to the outer periphery of said spring, its lower portion being designed to house said spring 30 and its upper end having an offset portion adapted to engage the upper end of said spring and to close said aperture when said sleeve is in its lowermost position, all of the parts being combined to form a separate unit attachable to the 35 neck of said container.

5. An automatic closing device for collapsible containers and the like, comprising in combination a neck having a right angled shoulder forming its base and being recessed on its under side, 40 thus adapted to be attached to the neck of said container, an outlet neck extending upward beyond said shoulder, a sliding sleeve, cylindrical in form, suspended around said neck, having an open lower end, the top being closed by a conoidal formation, the lower rim of which extends outward beyond the side wall, an orifice in the side wall adjacent said top, a coil spring mounted around said sleeve, its lower end abutting a flange extending outward around the bottom of 45 said sleeve, a housing and sealing unit mounted on said shoulder of said neck, its upper portion having an extension adapted to contact the upper end of said spring and to close said orifice by cooperating with the side wall of said sleeve, when said spring has returned said sleeve to its lowermost position, all the parts of said device 50 being combined as a separate unit to be attached to the neck of said container.

6. An automatic closing device for collapsible containers and the like, comprising in combination a hollow, cylindrical housing and sealing member, the same being a truncated paraboloid, having an internal, right angled shoulder in its upper portion, the inner wall extending upward and, due to its formation, terminating in a narrow rim, a core, open at the bottom, closed at the top by a conoidal formation, slidably suspended at its lowermost position by means of a protruding lip extending beyond the side wall 65 at the base of said conoidal formation at the top of said core, said protruding lip engaging the rim of said housing and sealing member, a coil spring mounted in surrounding relation to said core, its lower end positioned on an external, right an- 70

- gled shoulder at the lower end of said core, its upper end being engaged by said internal shoulder in the upper portion of said housing and sealing member, said core having an aperture through 5 the side wall adjacent the top, a neck member, open at the bottom end having an external, right angled shoulder forming its base which is recessed on its under side and a tubular outlet nozzle extending upward beyond said shoulder, 10 10 the said housing and sealing member with the said core slidably suspended within being mounted on said shoulder forming the base of said neck, said core being so dimensioned as to permit it to be slidably suspended on said outlet neck 15 15 above said shoulder, and movable upwardly when pressure is applied to said container, permitting said aperture in said core to rise above the rim of said housing and sealing member and allow contents of said container to be discharged, said 20 20 spring by virtue of its retaining agencies, automatically returning said core to its lowermost position, closing said device by disposing said aperture beneath the rim of and within the side wall of said housing and sealing member and 25 25 forcing contact of said protruding lip at the top of said core with the rim of said housing and sealing member, all the parts of said device being combined to form a separate unit which is attachable to said container.
- 30 7. An automatic closing device for collapsible containers and the like, comprising in combination a container having an elongated outlet neck with an external shoulder extending circularly at right angles around its base, a truncated housing member open at both ends and having an internal shoulder formation adjacent its upper end, a hollow core, cylindrical in form, open at the lower end, an aperture through the side wall adjacent the top, the top being closed by a conoidal formation and slidably suspended at its lowermost position within said truncated housing member by means of a protruding lip extending beyond the side wall at the base of said conoidal formation at the top of said core, said protruding lip engaging the upper rim of said truncated 35 35 housing member, a coil spring mounted in surrounding relation to said core, its lower end abutting a right angled flange extending circularly around the bottom end of said core, its upper end contacting said internal shoulder, the said truncated housing member with said core suspended within being mounted on said shoulder at the base of said elongated neck of said container, said core being reciprocally suspended around 40 40 45 45 50 50 55 55 60 60 65 65 70 70 75 75 80 80 85 85 90 90 95 95 100 100 105 105 110 110 115 115 120 120 125 125 130 130 135 135 140 140 145 145 150 150 155 155 160 160 165 165 170 170 the device on the outside by the said rim at the top of the said housing and sealing member making contact with the said protruding lip at the top of said sliding sleeve, all the parts of the said closing device being combined to form a separate unit which is attached to the neck of said container.

11. An automatic closing device for collapsible containers and the like, comprising in combination 10 a conoid, the lower portion being a truncated paraboloid, the upper portion of said conoid having a hollow tube attached at its base, extending downward and being slidably suspended within the lower portion of said conoid, a resilient member 15 reposing in surrounding relation to said tube providing the means of normally maintaining the upper portion of said conoid in sealing contact with the upper rim of said truncated paraboloid, a container having an outlet neck 20 with a shoulder at its base, said neck being reciprocally inserted within said tube attached to the base of the upper portion of said conoid, the lower portion of said conoid or truncated paraboloid being attached to said shoulder at the 25 base of said outlet neck, all of the parts being assembled in combination with said container to

form said closing device as a unitary part of said container.

12. An automatic closing device for collapsible containers and the like, comprising in combination 5 a conoid, the lower portion being a hollow truncated paraboloid open at both ends, the upper end terminating in a narrow rim, the vertex of said conoid having a tubular extension attached to its base, said extension being slidably inserted within the said truncated paraboloid, the said 10 tubular extension having a discharge orifice located in its side wall at the juncture with said vertex, a resilient member installed in surrounding relation to said tubular extension adapted to normally maintain said discharge orifice beneath 15 the rim of and within the confines of the said truncated paraboloid, a container having an outlet neck with a shoulder at its base, the said neck being inserted within said tubular extension, the said truncated paraboloid being attached to said shoulder at the base of said outlet neck, all of the parts being assembled in combination with said 20 container to form said closing device as a unitary part of said container.
